CLAIM

The ornamental design for a ceiling or wall-mounted TV monitor support, as shown and described.

DESCRIPTION

FIG. 1 is a bottom, front, and right side perspective view of a ceiling or wall-mounted TV monitor support showing our new design;
 FIG. 2 is a reduced rear elevational view thereof;
 FIG. 3 is a reduced right side elevational view thereof, the left side being a mirror image of that shown;
 FIG. 4 is a reduced bottom plan view thereof; and,
 FIG. 5 is a reduced front elevational view thereof.

FIG. 2

FIG. 4

FIG. 1

FIG. 3

FIG. 5
